UNITED STATES PATENT OFFICE.

CHARLES H. McBRIDE, OF INDIANAPOLIS, INDIANA.

RAIL-TIE.

1,174,259.

Specification of Letters Patent.

Patented Mar. 7, 1916.

Application filed February 13, 1914. Serial No. 818,524.

To all whom it may concern:

Be it known that I, CHARLES H. McBRIDE, a citizen of the United States, residing at Indianapolis, in the county of Marion and 5 State of Indiana, have invented certain new and useful Improvements in Rail-Ties; and I do hereby declare the following to be a full, clear, and exact description of the invention, such as will enable others skilled 10 in the art to which it appertains to make and use the same.

My invention relates to new and useful improvements in rail ties and resides in the provision of a preferably metallic rail tie 15 which is formed in two parts and provided with spring means whereby a greater resiliency is provided than is the case with the ordinary wooden tie, and more durability and strength than is embodied in the ordinary wooden tie.

Another important object of my invention is to provide a rail tie of the character described which will effectually prevent creeping and spreading of the rails which is often 25 resultant in wrecks and consequent loss of life, said functions being performed by a novel form of rail securing means forming a part of my invention.

A still further object of my invention is 30 to provide a tie which will remain firmly embedded in the road bed, consists of few parts and is cheap to manufacture.

The above and additional objects are accomplished by such means as are illustrated 35 in the accompanying drawings, described in the following specification and then more particularly pointed out in the claim which is appended hereto and forms a part of this application.

With reference to the drawings, wherein 40 I have illustrated the preferred embodiment of my invention as it is reduced to practice, and throughout the several views of which similar reference numerals designate corresponding parts. Figure 1 is a top plan view 45 of my rail tie showing the fastening holding a rail upon one end thereof. Fig. 2 is a longitudinal fragmentary sectional view taken on line 2—2 of Fig. 1 showing the detail 50 construction of the tie. Fig. 3 is a top plan view of the tie with the outer or top casing removed. Fig. 4 is a detail plan view of the rail clamping means, and Fig. 5 is a side elevation of a modified form of clamping 55 means.

Referring to the drawings the numerals

1 and 2 designate rectangular metallic casings each being open along one side and formed of some suitable metal. The casing 1 is disposed with its open side uppermost 60 and is slightly smaller than the casing 2 so that the casing 2 is placed over the casing 1 in slidable engagement therewith. The portions of each casing that are adjacent the ends are enlarged and reinforced as at 3 for 65 the purpose of giving strength to that portion of each casing wherein the weight of the rail and weight from the trains is placed. Adjacent each end of the casing 1 and centrally of the side edges thereof is formed an 70 upstanding lug 4 having its upper end spaced from the outer edge of the side walls, of the casing. Mounted upon the lugs 4 are helical expansion springs 5 having their terminals disposed in engagement with the casings 75 1 and 2. The lowermost edge of the casing 2 is normally spaced from the lowermost edge of the casing 1 and it will be readily seen that a great resiliency is provided the tie through the medium of the springs 5. 80

As a means for securing the rails A upon the tie I preferably provide rail clamping means designated 6 as an entirety. This rail clamping means consists of coacting clamping plates 7 and 8 provided with rail base angular clamping flanges 9 and 10. Each plate is provided with an outer edge opening longitudinal slot 11 arranged to receive a bolt 12 or other suitable fastening means that is inserted through the upper face of the casing 2. The plate 7 is provided adjacent its inner edge with an offset portion 13 that is arranged in spaced relation to the base of the casing 2 when in assembled position and in bearing engagement with the rail base. This offset portion 13 is preferably the same width as the rail base and is arranged to coöperate with an extended portion 14 formed integral with the inner edge of the clamping plate 8. The extended portion 14 is adapted to lie beneath and in engagement with the offset portion 13. It will be readily seen that the clamping of the rail A is provided in a reliable and efficient manner. 95 100 105

Referring particularly to Fig. 5 wherein I have illustrated a modified form of rail clamping means, the numeral 15 designates an approximately rectangular plate that is provided with longitudinal end opening slots 16 to receive suitable fastening means after the same manner as in the preferred 110

- form. This plate 15 is provided intermediate and at a point approximately centrally of its ends with spaced angular and integrally formed rail base engaging flanges 17.
- 5 It is to be understood that while I have shown and described a metallic tie consisting of metal casings 1 and 2 that other suitable material such as concrete or the like may be used.
- 10 It will be readily seen that all shocks or jars incident to the passing of trains over the rails A will be taken up by the springs 5 and that accidental derangement of the rails is prevented in that the shock in no 15 way serves to loosen the bolts or coöperating parts that are used for clamping the rails. The depressing of the outer casing 2 serves to keep the tie in the proper embedded position upon the road bed.
- 20 In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion, and arrangement of parts may 25

be resorted to, when required, without sacrificing any of the advantages of my invention, as defined in the appended claim.

What is claimed is:—

A rail tie comprising, a pair of rectangular metallic telescoping casings, one wall of each casing having thickened portions at its opposite ends extending into the terminals of the said ends, the said thickened portions on the wall of one casing being opposed to the thickened portions on the wall of the other casing, vertically disposed lugs carried by the thickened portions of one casing and arranged in spaced relation to the thickened portions of the other casing, springs surrounding the lugs and bearing against the opposed thickened portions of the casings, rail securing plates carried by the thickened portions of one of the casings, and fastening means extending through the plates and through the adjacent thickened portions of the casing.

In testimony whereof I affix my signature in presence of two witnesses.

CHARLES H. McBRIDE.
